Patented June 23, 1914

FIG.1.

FIG.2.

FIG.3.

UNITED STATES PATENT OFFICE.

EMILE GIRARDEAU, OF PARIS, FRANCE, ASSIGNOR OF ONE-HALF TO JOSEPH BETHENOD, OF PARIS, FRANCE.

AERIAL FOR WIRELESS TELEGRAPHY.

1,101,175.

Specification of Letters Patent. Patented June 23, 1914.

Application filed October 22, 1912. Serial No. 727,129.

To all whom it may concern:

Be it known that I, EMILE GIRARDEAU, a citizen of the Republic of France, residing at 128 Rue La Boétie, Paris, in the French Republic, have invented a certain new and useful Improvement in Aerials for Wireless Telegraphy, of which the following is a specification.

As is known the employment of high frequency alternating current generators for directly producing electromagnetic waves would present considerable advantages as compared with the production by the sudden discharge of a condenser by means of a spark gap or some similarly acting device. Unfortunately the production of alternating current generators for frequencies exceeding 10,000 periods per second is attended with great difficulty, so that it becomes necessary to provide aerial structures with a wave length of 30 km, and more.

The present invention has for its object an antenna of this kind which can be constructed in a relatively economical manner.

25 An embodiment of the invention is illustrated in the accompanying drawing, in which:

Figure 1 is a plan of the antenna. Fig. 2 represents a corresponding elevation. Fig. 3 illustrates the case in which a plurality of antennæ mounted in parallel, is available.

The wire F proceeding from the station S is composed in the known manner of two entirely different parts, that is to say of the part v which constitutes the effective (wave radiating) part and of a second horizontal part h, which radiates no waves. In accordance with the present invention the latter consists of a conducting wire stretched 40 in the form of a horizontal spiral. This may be effected for example by means of disk-shaped insulators I carried by connecting tensioning cables. If the total length of the horizontal wire h be designated L, the

45 wave length of the antenna would amount to $\frac{L}{4} \geq 4L$ (see J. Zenneck, "Leitfaden der Drahtlosen Telegraphie," chapter 11, page 38, 25^b). It will, therefore, be obvious that

in using masts P of moderate height (say up to 100 m.) and spacing them at the same 50 distance as an antenna with the usual extent of horizontal network, the wave lengths thus obtained may be very considerable.

It will of course be understood that the form of the spiral antenna can be modified 55 as desired, without thereby affecting the principle of the invention. Thus for example the number of masts can vary as desired and each part v or h can consist of a plurality of wires connected in parallel. 60

The mode of realization of antennæ according to the present invention can of course be applied to obtain all wave lengths, above or below the number of 30 km, cited aforesaid as example, either they are destined 65 for high frequency alternating current generator stations or for other systems as those using the oscillating discharge of a condenser or other phenomenon. It is also possible, as shown in Fig. 3, which is given 70 by way of example, to mount in parallel a number of antennæ arranged either in the same plane or in different planes.

If necessary a wire may be employed for joining the extremities of a number of antennæ thus combined in order to balance the tension at the extremity of the wires. 75

What I claim and desire to secure by Letters Patent of the United States is:—

An antenna for wireless telegraphy stations with high frequency alternating current generators, in which the conducting wire or wires consists of two parts, one part which forms the active part and a generally horizontal part, which radiates little or none 85 and which serves for increasing the wave length, this latter part being coiled and constructed as a flat sensibly horizontal spiral, presenting angles or affecting a more or less rounded form. 90

In testimony whereof I affix my signature in presence of two witnesses.

EMILE GIRARDEAU.
